UNITED STATES PATENT OFFICE.

WILLIE B. WHITE, OF CLEVELAND, OHIO.

DESIGN FOR A BODY FOR SPEED-WAGONS.

SPECIFICATION forming part of Design No. 29,771, dated December 6, 1898.

Application filed November 13, 1897. Serial No. 658,502. Term of patent 7 years.

To all whom it may concern:

Be it known that I, WILLIE B. WHITE, a citizen of the United States, residing at Cleveland, in the county of Cuyahoga and State of Ohio, have invented and produced a new and original Design for a Body for Speed-Wagons, of which the following is a specification, reference being had to the accompanying drawings, showing a part thereof.

10. In the accompanying drawings, Figure 1 is a plan view of a wagon-body, showing the form of my new design. Fig. 2 is a side elevation thereof.

As shown in the drawings, the leading and 15 material feature of my design consists in a

wagon-body open across its entire top and fashioned with straight parallel sides 2 and rounded ends 3 and 4 in the same vertical plane as the sides, and the whole constituting a body for speed-wagons.

20

What I claim is—

The design for a speed-wagon body, substantially as shown and described.

Witness my hand to the foregoing specification this 7th day of October, 1897.

WILLIE B. WHITE.

Witnesses:

H. T. FISHER,
R. B. MOSER.
